United States Patent Office

Des. 211,900
Patented Aug. 6, 1968

211,900

CIGARETTE LIGHTER

Takeshi Mizutani, Tokyo, Japan, assignor to
Kanamaru Shoten, Ltd., Tokyo, Japan

Filed July 5, 1967, Ser. No. 7,715

Term of patent 14 years

(Cl. D48—27)

FIG. 1

FIG. 2

FIG. 3

FIG. 4

FIG. 5

FIG. 1 is a perspective view of lighter in closed position embodying the present design;

FIG. 2 is a side view of the lighter in closed position;

FIG. 3 is a top view of the lighter in closed position;

FIG. 4 is a perspective view of the lighter in open position; and

FIG. 5 is a side view of the lighter in open position.

The characteristic feature of my lighter resides in the specific appearance of the windguard as best illustrated in FIGS. 4 and 5.

I claim:

The ornamental design for a cigarette lighter, as shown and described.
